[57] CLAIM

The ornamental design for a beverage container, as
shown and described.

DESCRIPTION

FIG. 1 is a front elevational view of a beverage container showing my new design;
 FIG. 2 is a right side elevational view thereof;
 FIG. 3 is a left side elevational view thereof;
 FIG. 4 is a top plan view thereof;
 FIG. 5 is a bottom plan view thereof; and
 FIG. 6 is a perspective view thereof on a reduced scale,
 the broken lines being illustrative of the environmental
 structure.
